UNITED STATES PATENT OFFICE.

ROBERT T. BROWN, OF BOSTON, MASSACHUSETTS, ASSIGNOR OF ONE-HALF TO F. WILLIAM BROWN, OF BOSTON, MASSACHUSETTS.

CONCRETE CONSTRUCTION.

No. 902,204.

Specification of Letters Patent. Patented Oct. 27, 1908.

Application filed February 1, 1907. Serial No. 355,294.

To all whom it may concern:

Be it known that I, ROBERT T. BROWN, a citizen of the United States, and a resident of Boston, in the county of Suffolk and State 5 of Massachusetts, have invented a new and useful Improvement in Concrete Constructions, of which the following is a specification.

My invention relates to concrete constructions and its object is to provide such a construction whereby the weight thereof may be reduced, and whereby a considerable economy in time and skilled labor, and hence in cost, may be effected without reducing the 15 stability, strength, or weight-sustaining qualities of the members of said construction.

With this object in view my invention comprises essentially a ventilated, reinforced, molded, concrete plank of any suitable shape, 20 preferably trapezoidal in cross-section, and various forms of construction embodying the same as particularly pointed out in the appended claims.

In the drawings which accompany and 25 form a part of this specification I have illustrated several embodiments of my invention which have been found well adapted in practice for effecting the foregoing objects; although it is to be understood that I do not 30 limit myself to the details of construction shown inasmuch as many modifications may be made therein by those skilled in the art without departing from the principles of my invention.

35 In the drawings Figure 1 shows a perspective view of an outside curtain-wall or inside partition, such for example, as the lining of an elevator shaft, constructed in accordance with my invention. Fig. 2 represents a horizontal section of the construction as shown 40 in Fig. 1. Fig. 3 shows a vertical section of a curved arch construction embodying one form of my molded concrete plank. Fig. 4 shows a vertical section taken on the line 45 4-4 of Fig. 3. Fig. 5 shows a vertical section of a flat arch construction embodying the use of my concrete plank. Fig. 6 shows a vertical section taken on the line 6-6 of Fig. 5. Fig. 7 shows in perspective one type 50 of mold whereby the aforesaid concrete plank may be formed. Fig. 8 shows a modification which may be employed in constructions of the type shown in Fig. 1.

In the figures, 1 represents a molded concrete plank, preferably trapezoidal in shape,

having one side A about five inches in width and its broader side B about six inches in width and being about three inches in thickness and from nine to ten feet in length.

Referring more particularly to Fig. 7, reinforcing, consisting, as shown in the present case, of iron or steel rods 2, are inserted through the two lower holes 13' in the ends of the mold, and concrete or other cementitious material is then packed into the mold 60 and up to the level of the preferably oval-shaped hole 14. An oval shaped tube or blocking of wire netting or perforated metal is then placed in the mold and held in position by the holes 14, 14 and two other reinforcements are placed in position through the upper holes 13, 13. The mold is then filled with concrete or other cementitious material packed and leveled off and allowed to harden. 65 After the concrete has hardened, the mold 70 is inverted and the concrete plank removed therefrom. This concrete plank, as shown for example in Fig. 2, reinforced by the rods 2 and ventilated by the hole 3, is then ready 75 to be used in various building constructions. 80

In the construction shown in Fig. 1, which is that of a curtain wall for steel-frame buildings, the concrete planks 1 are held at top and bottom in channel irons or by other suitable means, which in turn are secured to 85 the I-beams and girders of the usual type constituting steel-frame construction. As shown in Figs. 1 and 2, the planks are placed so that the broader side of every alternate plank faces outward. By virtue of the air-hole 3 the weight of the plank is reduced and the plank is made more impervious to the passage of sound or fire therethrough and can better withstand the action of heat. When the plank above described is used as an outside 90 wall or inside partition I prefer to employ two series of planks forming two parallel walls or partitions in lieu of a solid wall of double the thickness of a single plank in order more thoroughly to render the whole 95 100 impervious to the passage therethrough of sound and fire and to the action of heat.

By means of a suitably formed mold, which in view of the specific description of the mold shown in Fig. 7 it will be unnecessary to illustrate herein, a curved plank 1' reinforced by the rods 2' may be constructed 105 for use in forming floor arches as shown in Figs. 3 and 4. In setting up said arches the broader side of each plank is supported 110

upon the lower flanges of the I-beams 5 5 and the space formed between the top of the arch and the webs and upper flanges of the said I-beams is filled with fire-proof material 5 such as ashes, sand, cement, gravel, etc., as shown at 6. The floor beams 7 are then supported on the surface of said fire-proof material. A concrete ceiling 8 reinforced by the rods 9 may be hung from the lower 10 flanges of the I-beams and, if such construction is employed, the rods 9 may be bent up as shown over the lower flanges of said I-beams, before the curved planks 1' are placed in position. As shown more clearly 15 in Fig. 4 the cementitious or fire-proof material 6 fills the interstices between the adjacent planks 1' thus binding the several members of the arch.

Figs. 5 and 6 show the adaptation of my 20 invention to a flat arch in which as before the hung ceiling 8 may be employed. The concrete beams 10 reinforced by the rods 11 may be secured in position on the lower flanges of the I-beams 5 and the flat concrete 25 plank 1, reinforced by the rods 2 and ventilated as shown at 3, may then be supported by said beams 11. Here again the broader side of each concrete plank is placed downward and fire-proof or cementitious material 30 is packed in the space between the upper surface of the arch and the upper flanges of the I-beams.

As shown in Figs. 3 and 5 an air space is 35 formed between the upper portion of the hung ceiling 8 and the lower surface of the planks 1 or 1', said air space together with the air spaces 3 rendering the floor construction impervious to the passage of heat and sound.

40 As shown in Fig. 8, the planks 1'' may be formed with V-shaped ends and so arranged in their supports, such as the channel irons 4 4, which are shown in Fig. 1, as to leave narrow vertical spaces between the adjacent 45 planks. The outer surface of the wall so constructed may then be plastered or finished in any desirable way and a portion of said plaster or finish will enter into the angular spaces between each pair of adjacent 50 planks so as to more firmly secure the same to the surface of the wall.

I claim:

In a concrete construction, the combi-

nation with supporting I-beams, of an arch, 55 said arch consisting of a series of reinforced, molded, concrete planks trapezoidal in transverse section and each provided with a longitudinally extending cavity, said planks having their ends resting on and supported by the lower flanges of said I-beams and the 60 broader side of each plank being downward, whereby V-shaped spaces are formed between adjacent planks; and a layer of cementitious material superimposed upon said arch and filling said spaces. 65

2. In a concrete construction, the combination with supporting I-beams of a curved arch, said arch consisting of a plurality of contiguous reinforced, molded, concrete planks trapezoidal in transverse section and 70 each provided with a longitudinally extending cavity, said planks having their ends resting on and supported by the lower flanges of said I-beams and the broader side of each plank being downward, whereby V- 75 shaped spaces are formed between adjacent planks; a layer of cementitious material superimposed upon said arch and filling said spaces; and a flat arch beneath said curved arch, said flat arch consisting of a series of 80 reinforced concrete planks, each having its reinforces resting upon the lower flanges of said I-beams and so arranged that an air-space is formed between said arches. 85

3. In a concrete construction, the combination with supporting I-beams, of an arch, 90 said arch consisting of a plurality of contiguous reinforced, molded concrete planks trapezoidal in transverse section and each provided with a longitudinally extending 95 cavity, said planks having their ends resting on and supported by the lower flanges of said I-beams and the broader side of each plank being downward, whereby V-shaped spaces are formed between adjacent planks; and a layer of fire-proof material superimposed upon said arch and filling said spaces and the space between the webs of said I-beams and the top of said arch. 95

In testimony whereof, I have hereunto 100 subscribed my name this 29th day of Jan. 1907.

ROBERT T. BROWN.
